United States Patent Office.

PIETRO CINQUINI, OF WEST MERIDEN, CONNECTICUT, ASSIGNOR TO
PARKER & WHIPPLE COMPANY.

Design No. 4,695, dated March 7, 1871.

DESIGN FOR A BELL-CRANK AND ESCUTCHEON.

The Schedule referred to in these Letters Patent and making part of the same.

I, PIETRO CINQUINI, of West Meriden, in the county of New Haven and State of Connecticut, have invented and produced a new and original Design for Bell-Crank and Escutcheon, of which the following is a specification.

My design consists of a bell-crank with a plain raised ledge around its edge, the recessed panel formed by said ledge being filled with scroll-work, and its escutcheon with a plain raised ledge around its edge contiguous to the screw-holes, and around its center, just inside of said screw-holes, thus forming recessed panels between the screw-holes, which panels are filled with scroll-work.

In the accompanying drawing—

Figure 1 is a front view of my design for the crank and escutcheon combined, and

Figure 2, a front view of my design for the escutcheon only.

A designates the escutcheon, and
B, the crank.

Around the edge of the crank B is a smooth plain ledge, *a*, a portion of which crank and ledge is covered by the knob C.

The space inclosed by the ledge *a* is interlaid with ornamental scroll or leaf-work.

The escutcheon A is ornamented by a similar ledge, *a*, which extends around its edge, around and contiguous to the screw-holes *c*, and around its centerpiece or hub D, just inside of the screw-holes *c*, thus forming the recessed panels *d* between the respective screw-holes, which panels are interlaid with ornamental scroll-work.

The escutcheon A may be applied to either crank or knob-shaft, as desired.

I claim as my invention—

1. The design for a bell-crank, with the ledge *a* around its edge and the scroll or leaf-work in the space inclosed by said ledge, substantially as described and shown.

2. The design for a bell-shaft or door-knob escutcheon, with the ledge *a* around its edge, the central hub, and contiguous to the screw-holes, and raised ornamental work in the space inclosed by said ledge, substantially as described and shown.

PIETRO CINQUINI.
